UNITED STATES PATENT OFFICE.

GEORGE F. CLEMONS, OF SPRINGFIELD, MASSACHUSETTS.

IMPROVED TUCK-CREASER AND GUIDE FOR SEWING-MACHINES.

Specification forming part of Letters Patent No. 90,340, dated May 25, 1869.

To all whom it may concern:

Be it known that I, GEORGE F. CLEMONS, of Springfield, in the county of Hampden, in the State of Massachusetts, have invented a new and useful Combined Tuck-Marker and Cloth-Guide for Sewing-Machines; and I do hereby declare that the following is a full and exact description thereof, reference being had to the accompanying drawings, and to the letters of reference marked thereon, making part of this specification.

Figure 1 is a plan view of the device. Fig. 2 is a side elevation thereof.

The nature of my invention consists, chiefly, in modifying the construction of my formerly patented cloth-guide and in adapting to it additional parts in such a manner that the combined device may be readily adjusted so as to be used on sewing-machines, either for guiding or for tuck-marking and guiding the cloth which is being sewed.

Characteristic features of the tuck-marking parts of the device are, first, making a knife-edge creasing or tuck-marking plate or blade adjustable in a line at right angles with the gage-face, so as to be used for marking tucks of various widths, and also making it removable, so as to use the device for cloth-guiding; and, second, the employment, in connection with the said creasing-blade, of a notched non-vibrating adjustable pressure-plate, which crimps and presses the cloth over the blade, and thereby marks or creases a line on the cloth for the tuck. This creasing-plate is also the cloth-guiding plate, and a novel feature of my use of it is that its constant pressure on the cloth at the creasing-blade and its tendency thereby to force or deflect the advancing cloth too strongly inward and toward the gage-face of the device are counteracted by adjusting the pressure-plate so as to simultaneously bear and press upon the cloth at or near its inner edge, and thus produce an opposite and outward deflection of the cloth, so that it is made to run straight through the sewing-machine.

Referring to the drawings for a description of the construction and operation of my said invention, the device is constructed upon a base-plate consisting of the blade part *a* and the shank *b*, the latter having longitudinal slots *c c c* made in it for adjusting and securing the device to the sewing-machine bed-plate, as is commonly done in cloth guides or gages.

d is a rigid plate lying over the base-plate *a*, and set parallel to it in position, as shown in the drawings, with its wide side turned down at right angles and soldered or securely fixed at its edge to the base-plate *a*, at right angles to it, flush with the line of the junction of the plate *a* and shank *b*, the part thus turned down and secured forming a gage-plate, *e*, for the device.

Underneath the plate *d* is a spring-plate, bent double to form two nearly equal and parallel parts or leaves, *g* and *h*, the upper one of which, *g*, is fastened at its end to the plate *d*, and the lower one, *h*, is fastened near its bow end to and carries a cloth guiding and creasing plate, *i*, transversely curved up in a segment of a circle, and having V-shaped notches cut across its lower side at right angles to it, at equal distances from each other, so as to form a scale to measure the desired widths apart of the tuck-marks.

The base-plate *a* has on its upper surface a graduated scale of distances corresponding with the distances apart of the notches on the guide-plate *i*, and forming an index for setting the knife-edge to mark any required width of tuck.

j is a thumb set-screw working vertically in the outer end of the plate *d*, and bearing at its lower end on the upper leaf, *g*, of the spring-plate.

k is a similar thumb-screw working in a projecting piece, *f*, of the plate *d*, and bearing at its lower end on the outer end of the lower leaf, *h*, of the spring-plate.

l is a longitudinal slot cut in the base-plate *a*.

m is a thin piece of spring-plate, having one end turned up at right angles and formed into a vertical knife-edge, *n*, for creasing a line in the cloth. The plate *m* is attached to the plate *a* by a sliding and pivoted rivet, *p*, which passes through *m* and the slot *l*. Its narrower end is bent to form a downward-bearing spring, which presses on the plate *a* and keeps the plate *m* in position longitudinally on the plate *d*. A projection, *o*, is punched up on the lower side of the spring, and it fits into the slot *l* and keeps the knife-edge *n* parallel with the line, as *q r*, of tuck-marking.

The gage-plate *e* is cut and turned up horizontally, forming the projection *f*, in which the screw *k* works, and leaving an open space in

the gage-face for the spring *h* and guide-plate *i* to work in.

The plate *m* is shown placed underneath the guiding and creasing plate *i* in Figs. 1 and 2, as it is used in tuck marking and guiding; and it is also shown in Fig. 1 slid out from under or removed from the guide-plate *i*, as required when using the device only for a cloth-guide. In this last-described adjustment the operation of the device is similar to that of my patented cloth-guide, the cloth being guided by adjusting the screws *j* and *k* so that they shall bear suitably on the springs *g* and *h* to produce such distribution of spring-pressure upon the guide-plate *i* as that it will press more upon the cloth outside than inside the line of seam being sewed, the principle of the guiding action being that when there is more pressure of the guide-plate on the cloth outside than inside the line of seam the cloth will be deflected toward the gage-face, and when there is more pressure inside than outside the seam the cloth will be guided away from the gage-face. Increasing the pressure of the screw *j* upon the plate *g* increases the pressure at the outer part of the guide-plate *i*, and increasing the pressure of the screw *k* upon the spring *h* increases the pressure at the inner part of the guide-plate *i*, so that by turning the screws *j* and *k* suitably the desired guiding action is given to the guide-plate *i* for guiding the cloth in sewing either wide or narrow seams and for heavy or light fabrics, different widths of seams and different fabrics requiring different guiding action of the plate *i*.

If it is desirable to construct the described device to be used for a cloth-guide alone, the knife-edge plate *m*, the slot *l*, and the notches in the guide-plate *i* may be dispensed with.

In using the described device as a tuck-marker the cloth is placed between the plates *a* and *i* and over the knife-edge *n*, with the edge of the cloth against the gage-face *e*, and on applying pressure of the screw *j* sufficient to form a crimped or creased line on the cloth by the knife-edge *n* and its engaging notch, as the cloth advances in sewing it, the pressure on the cloth by the guide-plate *i* at the knife-edge *n*, being well outside the line of seam *s*, will (on the principle of guiding action before stated) deflect the cloth too strongly against the gage-face *e*; but this too great inward guiding action is counteracted by the means described of turning the screw *k* and giving such pressure of the guide-plate *i* at its inner end upon the edge of the cloth as will produce an outward guiding action and cause the cloth to run straight through the sewing-machine; and the screws *j* and *k* may be so adjusted as to make the creasing and guiding action of the plate *i* guide the cloth straight either in marking wide or narrow tucks. The guide-plate *i* also serves to smooth and keep from doubling up or wrinkling of the cloth between its edge and the line of creasing by means of the plate *i* bearing on the cloth or its folds between its edge and the line of creasing.

The knife-edge plate *m* may be otherwise adapted to slide longitudinally on the plate *a* and to keep the knife-edge *n* in position on the plate *a*. For example, the plate *m* may extend across the plate *a* and have its sides turned down so as to clasp the side edges of the plate *a*.

In the described device the rigid plate *d*, connected with the parts *e* and *b*, (which form a sewing-machine gage,) and the guide-plate *i*, connected with the rigid plate *d* and the set-screws *j* and *k* by a double spring, *g* and *h*, form a cloth-guide similar in principle of construction and in operation to my cloth-guide formerly patented, and I therefore do not herein claim those features of the described device only so far as they are new in combination of parts.

I claim as new and of my invention—

1. The employment, in a tuck-marker for sewing machines, of an adjustable knife-edge plate and a notched non-vibrating spring-pressure plate, adapted together, substantially as set forth, for forming creases for tuck-marks upon the cloth being sewed, when used in combination with means which produce automatically, substantially in the manner set forth, the described counteracting cloth-guiding action.

2. In a tuck-marker for sewing machines, adapting the device to form a crease on the cloth and to guide it inward toward a gage-face while the cloth is being sewed by means of continuous automatic pressing and crimping of the cloth over a knife-edge plate, and also adapting the device to produce simultaneously an outward counteracting guiding of the cloth by means of automatic pressure upon it at another point at or near its inner edge, for the twofold purpose of tuck-marking the cloth and guiding it straight through the sewing-machine, and, further, in such devices, adapting them to give adjustable and variable spring-pressure upon the cloth at the line of creasing and at or near the inner edge of the cloth, for the purposes set forth.

3. The notched adjustable pressure-plate *i*, adapted both to crease and to guide the cloth, substantially as set forth.

4. The adjustable knife-edge plate *m*, in combination with the notched creasing and guiding adjustable pressure-plate *i*, when adapted together for the purposes set forth.

5. The combination of the adjustable knife-edge plate *m*, stationary base-plate *a*, and notched creasing and guiding adjustable pressure-plate *i*, when adapted together for the purposes set forth.

6. The adjustable knife-edge plate *m*, stationary base-plate *a*, notched creasing and guiding plate *i*, adapted together for the purposes set forth, and combined with a cloth-gage, when the latter is connected to the former by means which are adapted to give the described adjustable and variable spring-pressure to the creasing and guiding plate *i*, for the purposes set forth.

7. The combined tuck-marker and cloth

gnide, consisting of the base-plate *a*, slotted gage-shank *b*, rigid plate *d*, gage *e*, spring-plates *g* and *h*, creasing and guiding plate *i*, set-screws *j* and *k*, and adjustable knife-edge plate *m*, all substantially as and for the purposes set forth.

8. The cloth-guide consisting of the base-plate *a*, slotted gage-shank *b*, rigid plate *d*,

gage *e*, spring-plates *g* and *h*, cloth guiding plate *i*, and pressure set-screws *j* and *k*, all substantially as and for the purposes set forth.
